WILLIAM RUBLEY, OF TUCKAHOE, NEW YORK.

GREASE-CUP.

1,278,024.

Specification of Letters Patent.

Patented Sept. 3, 1918.

Application filed April 27, 1916. Serial No. 93,817.

To all whom it may concern:

Be it known that I, WILLIAM RUBLEY, a citizen of the United States, and a resident of Tuckahoe, in the county of Westchester, 5 and State of New York, have invented certain new and useful Improvements in Grease-Cups, of which the following is a specification.

The invention is a grease cup combining certain features of construction and relation of a simple and practical character, enabling the grease holder to be removed, filled and replaced quickly and conveniently, causing it when in place to be securely held, 15 and insuring cleanliness. Since grease cups are of necessity frequently placed in inconvenient locations, the advantage of an organization whereby the grease receptacle and plunger are removable by a quick one-hand movement, as in the examples herein-after described, will be readily appreciated.

In the accompanying drawings illustrating certain of the possible forms of the invention:

Figure 1 is an elevation of a cup embodying the invention;

Fig. 2 is an enlarged section taken in an axial plane;

Fig. 3 is a fragmentary elevation of the removable part of the cup, showing one form of quick-acting screw;

Fig. 4 is a section on the line 4—4 of Fig. 2;

Fig. 5 is an axial section through another form of grease cup embodying the invention;

Fig. 6 is a fragmentary view, partly in elevation and partly in section, of still another embodiment, the parts being shown in relation for assembling; and

Fig. 7 is a fragmentary side sectional elevation of yet another embodiment.

Reference will first be had more particularly to Figs. 1 to 4.

The grease cup comprises a stationary part and a removable part. The stationary part comprises a shell 1, which is provided with a hollow stem 2, for attachment to the region to be lubricated, and the upper or outer edge of which has locking formations or ratchet teeth 3. The removable part includes a barrel 4, for the reception of the grease, this barrel being inserted into the shell, with which it has a screw connection, comprising threads 5 and 6 cut on the barrel and shell, respectively. In order to en-

able the barrel to be readily removed and preferably by only a partial turn, the screw connection is made of a quick-acting character, which may be accomplished as indicated in Fig. 3 by the use of a multiple thread, which on the barrel is confined to an upper region, leaving the lower part of the barrel plain as shown at 7. It is immaterial whether the stationary shell be threaded throughout as in Fig. 2 or only at the top, as shown in Fig. 5. The removable barrel occupies a fixed position when in place, with its lower or inner edge bearing against a packing washer 8 at the bottom 70 of the shell, this seat being the only limit to the inward movement of the barrel when the latter is inserted. The grease is delivered from time to time by means of a plunger carried by and adjustable in the barrel. In 75 Figs. 1, 2 and 4 this plunger comprises a disk 9 of suitable material, secured to a screw-threaded spindle 10, which operates in an internal thread in a neck or nut member 11 united with the top of the barrel, the 80 outer end of the spindle being provided with a handle 12. A compression spring 13 confined between the disk 9 and the top of the barrel takes up all looseness between the threads of the spindle and neck, in order 85 that the adjustment of the plunger may not be disturbed as the result of vibration.

A rigid, spring-pressed locking member 14 is mounted on the removable grease-holding barrel 4, to coöperate with the locking formations on the stationary shell 1, for the purpose of preventing accidental unscrewing of the quick-acting connection between these parts. In the preferred form this locking member is arranged as a cap, having a top wall provided with a square opening 15 for slidable reception of the neck 11, and a circular wall 16 surrounding the upper part of the barrel and formed on its lower or inner edge with ratchet teeth 17. 100 A compression spring 18 interposed between the top wall of the cap and a collar 19 on the neck 11, and housed by a flanged washer 20, urges the locking member inward so as to engage its teeth with those of the stationary shell. The externally located locking member thus affords a hand grip, for unlocking and unscrewing the barrel, for which purposes the external surface of its circular wall may be roughened as 110 shown at 21.

It will be obvious, however, that the form

of the rigid locking member may be varied, as also its manner of connection with the removable barrel, so long as it is slidable but substantially non-rotatable thereon. In 5 operation the barrel is unlocked and removed by a pull and a twist, the locking member being grasped and moved outward to free the locking formations, and then turned, the latter movement causing the 10 barrel to turn also. By virtue of the quick-acting connection between the barrel and shell, the separation may be effected by a fractional turn, the whole operation of unlocking and taking off the barrel being performed without shifting the hand upon the 15 grip, and by substantially a continuous manual movement. When the barrel has been removed, the plunger is run back and the barrel filled. The barrel is then reinserted in the shell and by a turn equal to that required for its removal seated firmly upon the gasket 8, the assembling operation being facilitated by the presence of the plain portion or ferrule 7, which serves to 20 guide the entrance of the barrel into the shell and to assist the engagement of the threads. While the barrel is being screwed home the inclined sides of the ratchet teeth ride past each other idly, the spring 18 yielding to the consequent movement of the locking member and insuring engagement of the teeth when the barrel is home, irrespective of variations in the thickness of the washer. 25 In order to enable the teeth to have full engagement with each other at any point in the turning of the barrel when the latter comes to rest against the gasket, the opening 15 is preferably made a little large for the neck 11, as shown in Fig. 4, so that the locking member, while substantially non-rotary upon the barrel, as already stated, is still capable of a slight relative turning movement, sufficient to enable its locking 30 formations to take properly into those of the shell when the assembling of the cup is completed.

Fig. 6 illustrates as another form of quick-acting screw connection between the removable barrel 4^a and the stationary member 1^a, 50 a breech-block joint comprising screw threads 5^a and 6^a (not multiple threads) interrupted by plain areas 5^b and 6^b. With this construction the cup is put together by entering the barrel into the shell in the relation shown in the view until it touches or 55 nearly touches the compressible gasket 8, and then giving it a slight turn, so as to engage the threaded areas and cause the barrel edge to be crowded against the washer. 60 In this way the barrel can be removed and replaced with a very short turning movement, but, nevertheless, when in assembled position is securely held by the locking means. Both in this and in the preceding 65 construction the quick-acting screw means

uniting the two parts of the cup is not relied upon to form a grease-tight joint. This is effected instead by the pressure of the barrel edge upon the gasket 8, which prevents grease getting upon the outside of the barrel and thereby soiling the hand when the barrel is removed.

The modification in Fig. 5 relates to the plunger. Here the spindle 10^a is not threaded, and is held against longitudinal movement in its bearing in the top of the barrel. Its lower part 10^b is of square or other appropriate cross-section, permitting the disk 9^a, which is formed of metal with a corresponding aperture in its center, to move longitudinally while compelled to turn with this shank portion. The edge of the disk is cut with screw threads, which fit threads 25 on the inner face of the barrel, so that the turning of the disk causes it to move inward or outward, as the case may be. The advantage of this arrangement is that the spindle and spindle handle do not have to move lengthwise, and consequently the cup may be installed in locations where the lack of space is such as to necessitate a comparatively low structure.

Fig. 7 illustrates the fact that ratchet teeth 3^a may be employed, the sides of which slope in both directions, so that a turning movement is all that is necessary to remove the barrel. In this instance the hand grip 21^a is shown as being formed on the periphery of a disk 19, which, like the collar 19 of the other views, is united with the neck 11 of the removable grease-containing barrel. When the user wishes to take out the barrel, he merely grasps this hand-hold and turns it for a part of a revolution in the unscrewing direction without pulling outward. In this operation the oblique faces of the ratchet teeth ride over each other, the locking member 14^a rising and falling as they do so.

The foregoing constitute only a few of the variations of which my invention is susceptible, and it is to be understood that I do not necessarily limit myself to any of the particular forms of the grease cup and its elements which I have illustrated and described as constituting preferred exemplifications.

What I claim as new is:

1. In a grease cup, the combination of a stationary shell, a removable barrel entering the shell and having screw connection therewith, said shell and barrel having a quick-acting screw connection therebetween, a plunger carried by and adjustable in the barrel, a tight seat for the lower end of the barrel, said seat constituting the only limit to the entering movement of the barrel into the shell, and a rigid spring-pressed locking member slidably guided on the removable barrel for engagement with the shell.

2. A grease cup comprising the combination of a stationary shell having locking formations, a removable barrel entering the shell, said shell and barrel having a quick-acting screw connection therebetween, a plunger carried by and adjustable in the barrel, and a longitudinally movable spring-pressed combined locking member and hand grip also carried by the barrel.
3. A grease cup comprising a stationary shell having locking means formed thereon, a removable barrel for reception of the grease, said barrel entering the shell and having screw connection therewith, a plunger carried by and adjustable in the barrel, and a spring-pressed locking member encircling the barrel and having a series of teeth, said member being mounted on and having connection with the removable barrel whereby it may move longitudinally and to a slight extent rotatably thereon in order to engage and disengage the locking means on the shell and to have full engagement therewith when the barrel is seated.
4. A grease cup comprising a stationary part having an outlet, and a removable part, said removable part including a barrel to receive the grease, a plunger adjustable in the barrel to deliver the grease through the outlet of the stationary part, a spring-pressed longitudinally movable locking member on the barrel for engagement with the stationary part, and a hand grip connected with said locking member whereby it is releasable by an outward movement of the hand preparatory to unscrewing the barrel from the stationary part.
5. In a grease cup, the combination of a shell constituting the stationary part of the cup, a removable barrel for reception of the grease having screw connection with the stationary shell, a plunger carried by and adjustable in the barrel, and a spring-pressed longitudinally movable locking member carried by the removable barrel for engagement with the stationary shell, said locking member having means whereby it is released by an outward movement of the hand preparatory to unscrewing the barrel.
6. A grease cup comprising a stationary part, a removable barrel for the reception of the grease having screw connection with the stationary shell, a plunger carried by and adjustable in the barrel, and a longitudinally movable spring-pressed hand grip on the barrel for unscrewing the same, said stationary part and hand grip having means for locking the barrel to the shell releasable by an outward movement of said hand grip.
7. A grease cup comprising a stationary part having locking formations, a removable barrel having a neck, a plunger having a spindle passing through said neck, and a spring-pressed cap on the barrel having slidale and substantially non-rotatable engagement with the neck, said cap having locking formations to engage those on the stationary shell.

WILLIAM RUBLE.
